CLAIM

The ornamental design for an oxygen supply bracket for a hospital transport cart, as shown and described.

DESCRIPTION

FIG. 1 is a perspective top and side view of an oxygen supply bracket for a hospital transport cart showing my new design;

FIG. 2 is a top view thereof;

FIG. 3 is a front view thereof;

FIG. 4 is a right side view;

FIG. 5 is a left side view;

FIG. 6 is a bottom view; and,

FIG. 7 is a sectional view taken in the direction of the arrows upon the line 7—7 of FIG. 2 with the broken line showing of an interactive oxygen in feed line, pressure gauge and control valve being for illustrative purposes only and forming no part of the claimed design.
